UNITED STATES PATENT OFFICE.

WILLIAM C. HOPKINS AND JOHN W. MILLER, OF MUSCATINE, IOWA; SAID MILLER ASSIGNOR TO THE MCKEE AND BLIVEN BUTTON COMPANY, OF MUSCATINE, IOWA.

BUTTON-MACHINE.

No. 840,939.

Specification of Letters Patent.

Patented Jan. 8, 1907.

Application filed December 18, 1905. Serial No. 292,398.

To all whom it may concern:

Be it known that we, WILLIAM C. HOPKINS and JOHN W. MILLER, citizens of the United States, residing at Muscatine, Muscatine county, Iowa, have invented certain new and useful Improvements in Button-Machines; and we hereby declare that the following is a full, clear, and exact description thereof, reference being had to the accompanying drawings, which form part of this specification.

This invention is an improvement in machines for making buttons, and especially designed for producing "cat-eye" buttons, in which a narrow concave slit or groove is made in the upper surface of the button, in which groove the eyes are pierced.

The object of this invention is to enable the button-blanks to be operated on while they travel by means of mechanisms which will first face or round off the surface of the button; second, will cut the cat-eye slit therein, and, third, will drill the eyes in the button at the proper points, these several operations taking place successively on each blank as it passes through the machine, and all the operations may be performed simultaneously on different blanks as they travel, so that a plurality of buttons in different stages of completion are undergoing operations at the same time, and during the passage of each blank through the machine it is converted into a finished cat-eye button.

In the preferred form of the invention the blanks and tools are arranged to travel together during the working periods, and in the machine illustrated in the drawings the blank-carrying chucks move continuously in an orbital path while the tools oscillate in arc-shaped paths coincident with the path traversed by the blanks during the working operations, the tools traveling with the blanks while opening thereon and then moving back to meet an oncoming blank and traveling therewith until their operations thereon are completed. The invention, however, is not restricted to the particular form or construction of parts illustrated in the drawings, as when once understood it can easily be embodied in various mechanical forms, and we therefore refer to the claims for summaries of the combinations and constructions of parts embraced in the

present invention and for which protection is desired.

In said drawings, Figure 1 is a side elevation, partly broken, of a complete machine embodying the several features of the invention. Fig. 2 is an enlarged sectional view through one of the tool-carriers. Fig. 3 is a transverse section on line 3 3, Fig. 1. Fig. 4 is a detail view of the mechanism for depressing the tool-carrier. Figs. 5 and 6 are detail views illustrating the grinding operation. Figs. 7 and 8 are detail views illustrating the cat-eye operation.

In the drawings, 1 designates the main shaft of the machine, which is supported, preferably, in a vertical position in suitable bearings in a main frame of any suitable construction and can be rotated at any desired speed by means of a worm-wheel 1^a and worm 1^b, mounted on a counter-shaft 1^c, journaled on the frame and which can be driven in any convenient manner.

On shaft 1 is mounted a pair of similar disks 2, in which are rotatably mounted a series of equidistant vertically-disposed chuck-holders 2^a of any suitable construction, provided with friction-pulleys 2^b, adapted to contact during part of their travel with the inner run of an endless belt 3, running over belt-pulleys 3^a 3^b, suitably supported from the main frame, the shaft 3^c of pulley 3^b being driven by bevel-gearing 3^d from the counter-shaft 1^c, as indicated in the drawings.

In each chuck-holder 2^a is a blank-holding chuck 2^b, which may be of any preferred kind adapted to receive and hold a button-blank B, as indicated in the drawings. As the disks 2 rotate the several chucks are moved in an orbital path to, past, and from the inner run of the belt 3, and when they come up to this belt the pulleys 2^b on the chuck-holders contact the inner run of the belt 3, which causes the chuck-holders to rotate at a high speed on their own axes so long as they travel in contact with the belt.

The chucks 2^b (shown in the drawings) are adapted to be opened when pushed upwardly in the chuck-holders, and for this purpose a cam 1^b is fixed to the main frame in the path of the lower ends of the chucks, which strike said cam as they come thereto and are lifted thereby as they pass thereover and open, allowing the finished buttons to be removed.

therefrom and fresh blanks to be placed therein before the chuck-holders clear the cam, which they do just before reaching the belt 3. The chucks are normally pressed down and closed on the blanks by springs 2ⁱ, interposed between the lower ends of the chuck-holders and heads 2^j on the lower ends of the chuck-shanks.

Located above the disks 2 and in line with 10 the path circumscribed by the chucks is a button-facing device comprising a grooved emery or carborundum wheel 4, which is mounted on a shaft 4^a, journaled in a sleeve 4^c, which is adjustably supported in an arm 4^b, attached to and radiating from a sleeve 5, loosely surrounding shaft 1 above disk 2. The shaft 4^a has no longitudinal play in sleeve 4^c, but is provided with a belt-pulley 4^b on its end adjacent the grinding-wheel 4. (See 15 Fig. 2.) Sleeve 4^c is preferably non-rotatable in arm 4^b, but is adjustable longitudinally thereof, so as to adjust the grinder 4 radially of the disk. As shown, sleeve 4^c has a lug 4^e projecting through a slot in the side of the 20 arm and held between two adjusting-bolts 4^f, tapped through lugs 4^h on arm 4^b.

Arm 4^b is preferably adjustably attached to sleeve 5 by means of bolts 4ⁱ, passing through slots in lugs 4^j on the inner end of 25 said arm and tapped into the sleeve, (see Fig. 2,) and adjusting-bolts 4^k 4^m, tapped through lugs 5^a 5^b on the sleeve 5, enable the arm 4^b and the grinder to be adjusted vertically relative to the disks 2 and the chucks carried 30 thereby.

The grinder 4 may be rotated by means of an endless belt 4ⁿ, running over pulley 4^b up to, and over guide-pulleys 4° on a bracket 4^p, loose on shaft 1, and thence to a driving-pulley 4^q on shaft 1, as shown in the drawings, or 40 by any other convenient and preferred means.

About the time the chuck begins to be rotated on its own axis by means of belt 3 the 45 grinder 4 is lowered into contact with the blank B, held by the chuck, and begins to operate thereon. As the grinder rotates in a plane at right angles to the plane of rotation of the chuck the blank is very smoothly and 50 rapidly faced, and if a grooved grinder be used, as shown, a globular face will be quickly put on the blank. It is preferable to bring the grinder and blank into gradual contact by moving one toward the other, and this 55 may be accomplished either by moving the chuck and blank toward the grinder or moving the grinder toward the chuck.

As illustrated in the drawings, a collar 1^d is pinned to shaft 1 above the sleeve 5 and has 60 on its lower edge a series of cam-surfaces 1^e, (corresponding in number to the number of chucks carried by the disks 2,) which cam-surfaces successively act upon a push-pin 5^e, which is confined in a guide-slot in a non-rotatable bracket 5^b (which is rigidly connect-

ed to the main frame) and is interposed between the cam-collar 1^d and the upper end of sleeve 5, against which the lower end of the push-pin 5^e bears, so that as the cam 1^d rotates it pushes down pin 5^e, and thereby moves sleeve 5 and the parts attached thereto downward against the action of an expansion-spring 5^f, interposed between the lower end of sleeve 5 and the upper disk 2, and which spring tends to normally raise the 75 sleeve 5 and all attached parts. Thus the grinder is gradually lowered upon or against the blank and acts most effectively thereon. It is, however, desirable or necessary that the grinder travel with the blank during the 80 grinding operation, and for this purpose a set of studs 2^r (one for each chuck-holder) are attached to the upper disk 2 and are adapted to successively engage with a lug 4^r, depending from the under side of arm 4^b, so that at 85 the proper times the arm 4^b is caused to swing or turn with disks 2 and at exactly the speed of travel of the chucks, and it continues to travel therewith until push-pin 5^e rides over the lowest point of the then controlling 90 cam-surface 1^e on collar 1^d, whereupon spring 5^f throws up the sleeve 5 and attached parts, allowing lug 4^r to clear the stud 2^r, and thereupon the arm 4^b and sleeve 5 are swung back to first position until lug 4^r is contacted by a 95 succeeding stud 2^r, when the arm is caused to travel with the disks 2 and chucks, as just explained. The arm may be swung back when released by any suitable means. As shown, a small belt-pulley 5^r is attached to sleeve 5 100 and driven from a pulley 3^r on shaft 3^r by means of a belt 5^q, which belt slips on the pulleys during the positive movement of the arm 4^b, but will turn the sleeve and arm back as soon as lug 4^r clears the impelling-stud 2^r. Thus the chucks can travel continuously. They are rotated on their own axes during a certain part of their travel. The grinder is adapted to meet the chucks about the time they begin to rotate and travel therewith during part of their travel, and during such coincident travel the grinder and blank are gradually brought toward each other, so that the blank is finished off in the desired shape with precision. Owing to the direct gradual movement of the grinder toward the chuck, the blanks are not knocked out of the chucks by the initial contact of the grinder therewith.

The foregoing-described mechanism completes the first of the desired operations—that of facing the blanks—and this much of the mechanism could be usefully employed apart from the mechanisms which perform subsequent operations on the blanks.

The cat-eye mechanism.—The next succeeding operation in producing cat-eye buttons is to make the cat-eye slit, and this is preferably performed on the same machine by the following mechanisms: Attached to 130

sleeve 5 at a point adjacent arm 4^a—say about sixty degrees removed therefrom—is a second arm, which is or may be in all substantial particulars the same as arm 4, only it need not have the lug 4^r. On the shaft carried by this second arm is a grinding-wheel 4^s, which preferably has a double-beveled grinding-periphery, whose bevel corresponds with the pitch of the cat-eye slot to be cut in the blanks. This second arm 4 is so located and adjusted that cutter 4^a coincides with one chuck and can operate on a blank held thereby while the grinder 4 is operating on a blank held by a following chuck. Cutter 4^a is raised and lowered relatively to the chuck just as grinder 4 is, as above described. The grinder and cutter thus can operate simultaneously on different blanks, the cutter operating on a blank previously faced by the grinder at a preceding operation. In order that the cutter can operate properly on the blanks, however, it is necessary to stop the rotation of the chucks, and for this purpose just after the chucks leave the belt 3 a squared flange 2^m on the chuck-holders comes into contact with a curved rail or plate 1^m, attached to the main frame, (see Figs. 1 and 3,) and as the squared edge of such collar contacts with the flat side of the said rail the chuck-holder cannot rotate on its axis, although it can slide along the rail, and thus the chuck is held stationary on its axis while the cutter is operating on the blank held thereby. The cutter therefore meets the blank, and the two are gradually brought into contact, the beveled edge of the cutter making a concave arc-shaped slit in the blank diametrically thereof, as indicated in Fig. 8 of the drawings, giving the desired cat-eye appearance thereto. The cutter is lifted clear of the blank simultaneously with the raising of the grinder and moves back therewith into position to take up with and operate on the next blank at the proper moment. The operation of the cutter will be clear from the foregoing, and it is obvious that the cat-eye-cutting mechanism could be usefully employed apart from the grinding or drilling mechanisms. After the button-blanks are faced and cat-eyed they have to be drilled, and, while these operations may be performed in other machines, we provide mechanism for drilling them before they are discharged from the chucks, as follows:

55 *The drilling mechanism.*—Customarily but two eyes are drilled in cat-eye buttons, these being drilled in line within the cat-eye slit. Therefore two drills 6 are shown, each mounted in a spindle 6^a, journaled in lower bearings 6^b attached to arms 5^a, fastened to sleeve 5, and in upper bearings on arms 6^b, attached to a sleeve 6^c, loosely surrounding shaft 1 above cam-collar 1^d. The arms 6^b and 5^a may be rigidly connected by suitable ties 6^d, so that the drill-spindles will be kept in perfect aline-

ment and move synchronously. The drills are spaced apart the distance between two adjacent chucks and are separated from the cutter a suitable distance, so that when the grinder and cutter are operating on blanks 70 the drills may simultaneously operate on other blanks. In the machine shown four blanks can be operated on at one time, while at the same time the finished buttons are being removed and fresh blanks put into the 75 other chucks.

In the machine shown the drills move with the grinder and cutter both to and from the chucks and back and forth, traveling with the chucks during the drilling operations and 80 then shifting back to meet the succeeding blanks and operate thereon.

The drill-spindles can be rotated by any suitable means. As shown, pulleys 6^e on the upper ends of the spindles are engaged by an 85 endless belt 6^f, driven by a pulley 6^h, loosely journaled on shaft 1 above the sleeve 6^c, which pulley may be provided with a smaller pulley 6ⁱ driven by a belt 6^j from a pulley 3^j on shaft 3ⁱ, as shown. 90

It will be seen that the drills meet the blanks, travel therewith, gradually descend thereon, and perforate them as they travel and then rise clear of the blanks before they are moved back to first position. The drills 95 are so adjusted that the first drill cuts one eye in the button, and the next drill cuts the second eye, and the blanks when discharged from the machine will have been faced, cat-eyed, and drilled. 100

The mechanism shown for drilling could be usefully employed apart from the other mechanisms, if desired; but when the aforesaid mechanisms are combined as described a very simple and economical machine is produced wherein but one feeding operation is required, whereas if the mechanisms are put in separate machines additional feeding operations are necessitated, with a consequent increase in cost of production of the buttons. 110

While the mechanisms illustrated and described for operating the grinding, cutting, and drilling tools are at present preferred, it is obvious that various changes could be made therein within the scope of the present 115 invention, and therefore

What we claim, and desire to secure by Letters Patent, is—

1. In a button-machine, the combination of a rotatable blank-holder, a grinder adapted to rotate in a plane at right angles to the plane of movement of the blank-holder, means adapted to bring the blank and grinder into contact; and mechanism for traveling the blank holder and grinder in 120 unison during the grinding operation, substantially as described.

2. In a button-machine, the combination of a rotatable blank-holder adapted to move orbitally in one plane, a grinder adapted to 130

rotate in a plane at right angles to the plane of the blank-holder, and means adapted to bring the blank and grinder into contact; with mechanism for traveling the grinder in unison with the blank-holder during the grinding operation, and means for moving the grinder backward to starting position after each operation, substantially as described.

10. 3. In a button-machine, the combination of a blank-holder adapted to travel, a rotatable grinder having a concave grinding-surface, a reciprocatory support therefor, means adapted to bring the grinder into contact with the blank, means for rotating the blank during the grinding operation, means for moving the grinder in unison with the blank-holder during the grinding operation, and means for moving the grinder back to the starting-point after each operation.

11. 4. In a button-machine, the combination of a blank-holder adapted to travel; with a grinder, and a cat-eye cutter, adapted to successively operate on the blank, and means for traveling the grinder and cat-eye cutter with the blank-holder during the cutting operations.

12. 5. In a button-machine, the combination of a plurality of blank-holders adapted to travel; with a grinder, and a cat-eye cutter adapted to successively operate on the blanks; means for moving the grinder and cat-eye cutter with the blanks during their coöperation, and means for moving the tools backward to initial position after each operation.

13. 6. In a button-machine, the combination of a plurality of blank-holders adapted to travel; with a rotary grinder, and a rotary cutter adapted to operate simultaneously on different blanks, and successively on the same blank; means for moving the tools with the blanks during their coöperation, and means for moving the tools backward to initial position after each operation.

14. 7. In a button-machine, the combination of a blank-holder adapted to travel; with a grinder, a cat-eye cutter; means for moving the grinder and cutter with the blank-holder while coöoperating therewith; means for rotating the blank-holder on its axis while coacting with the grinder, means for stopping the rotation of the blank-holder while coöperating with the cutter; and means for moving the grinder and cutter back to initial position after their operations on the blank, substantially as described.

15. 8. In a button-machine, the combination of a blank-holder adapted to travel; with a cat-eye cutter and drills, adapted to successively operate on the blank, and means for traveling the tools with the blank while operating thereon.

16. 9. In a button-machine, the combination of a blank-holder adapted to travel, a cat-eye

cutter and drills, adapted to successively operate on the blank, and means for traveling the tools in unison with the blank while operating thereon; with means for advancing the tools to the blanks during their coincident travel, and means for separating the tools from the blank and moving them backward to initial position after each operation.

10. 10. In a button-machine, the combination of a blank-holder adapted to travel; with a cat-eye cutter and drills, adapted to successively operate on the blank; means for approaching the tools and blank during their operation; means for traveling the tools with the blank during their operation; means for preventing rotation of the blank while the cat-eye cutter is operating thereon, and means for separating the tools from the blanks and moving them backward to initial position after each operation.

11. 11. In a button-machine, the combination of a blank-holder adapted to travel, a blank-grinder, a cat-eye cutter, and drills, adapted to successively operate upon the blank carried by said holder, and means for moving the tools with the holder during the operations on the blank.

12. 12. In a button-machine, the combination of a blank-holder, a blank-grinder, a cat-eye cutter, and a drill, adapted to successively operate upon the blank carried by said holder; with means for advancing the tools against the blank while operating thereon, and means for separating the tools from the blanks and moving them backward to initial position after each operation.

13. 13. In a button-machine, the combination of a rotary main shaft, disks thereon, rotatable chuck-holders carried by said disks, chucks in said holders, a tool-carrier mounted loosely on the shaft above the disks, a horizontal rotary shaft mounted on said carrier adjacent the path of the chucks; a cutter on said shaft, a cam adapted to move the said carrier to cause the cutter to operate on blanks carried by the chucks; means for moving the carrier so as to cause the cutter to travel with the chucks during its operation; means for raising the carrier after each operation, and means for moving the carrier backward after each operation.

14. 14. In a button-machine, the combination of a rotary main shaft, disks thereon, rotatable chuck-holders carried by said disks, a tool-carrier loose on said shaft adjacent the disks, a rotatable grinder, a rotatable cat-eye cutter, and rotatable drills mounted on said carrier; means for moving the carrier so as to travel the tools with the chucks during the operations on the blanks; means for rotating the chuck-holders while moving with the grinder; and means for stopping the rotation of the chuck-holders while they are moving with the cat-eye cutter and with the drills, substantially as described.

15. In a button-machine, the combination of a rotary main shaft, disks thereon, rotatable chuck-holders carried by said disks, a tool-carrier loose on said shaft adjacent the 5 disks, a rotary grinder, a rotary cat-eye cutter, and rotatable drills mounted on said carrier; means for rotating said tools on their individual axes; means for moving the carrier so as to travel the tools with the chucks during 10 the operations of the tools on the blanks; means for depressing the carrier to cause the tools to gradually descend toward the blanks during their operations thereon; means for rotating the chuck-holders while moving 15 with the grinder; means for stopping the rotation of the chuck-holders while moving with the cat-eye cutter and with the drills; means for raising the carrier upon the completion 20 of the operations, and means for then moving the carrier backward, substantially as described.

16. In a button-machine, the combination with a blank-holder adapted to travel; of a tool-holder comprising a rotatable shaft carrying 25 the tool, a sleeve carrying the shaft, a movable support in which said sleeve is mounted, and means for moving said sup-

port to cause the tool to move with the blank-holder, substantially as described.

17. In a button-machine, the combination 30 with a blank-holder adapted to travel; of a movable arm, a sleeve adjustably mounted in said arm, a shaft rotatably mounted in said sleeve, and a tool carried by said shaft; with means for rotating said shaft, and means for 35 vibrating the arm to cause the tool to move with the blank-holder during its operation on the blanks.

18. The combination of a movable sleeve, 40 an arm adjustably attached to said sleeve, a sleeve adjustably mounted in said arm, a shaft rotatably mounted in said sleeve, and a tool carried by said shaft; with means for rotating said shaft, and means for vibrating the arm, substantially as described. 45

In testimony that we claim the foregoing as our own we affix our signatures in presence of two witnesses.
